UNITED STATES PATENT OFFICE

AXEL F. LARSON, OF CHICAGO, ILLINOIS, ASSIGNOR TO WESTERN ELECTRIC PIANO COMPANY, OF CHICAGO, ILLINOIS, A CORPORATION OF ILLINOIS

TALKING MACHINE

Application filed November 2, 1927. Serial No. 230,545.

One of my objects is to provide means, in a talking machine, whereby the machine may be operated to play a large number of selections without requiring the manual operation of changing the needle or stylus, the invention having particular application to machines which are placed in public places to be set into operation automatically by the deposit of a coin therein, in such machines it being particularly desirable that servicing of the machine, as for example to change the needle or stylus, be as infrequent as possible thereby to reduce the cost of operation.

Another object is to provide novel, simple and economical means for the purposes above stated.

Another object is to provide in a machine of the type in which the needle or stylus is so mounted that it moves across the record, for the engagement of the needle or stylus with the record at the desired point thereon, in the lowering of the needle or stylus to the record in the positioning of the parts to play a record, and other objects as will be manifest from the following description.

While my invention, as to certain phases thereof, may be embodied in machines of varying types and constructions, I have devised it for use more particularly in a machine of the type illustrated and described in the pending application for U. S. patent filed by Charlie W. Anderson and myself for improvement in talking machines, Serial No. 214,066, filed August 19, 1927, and have therefore chosen to illustrate my present invention in connection with a machine of this type, but without the intention, however, of limiting the invention, as to certain aspects thereof, to its incorporation in such type of machine.

Referring to the accompanying drawings:

Figure 1 is a broken plan view of a machine of the type shown in said application for patent, and in which my improvements are incorporated. Figure 2 is a view in vertical elevation of certain of the parts disclosed in Fig. 1, the tone arm of the device being broken away. Figure 3 is a similar view illustrating others of the parts shown in Fig. 1. Figure 4 is a view in side elevation of the

tone arm and the reproducer device. Figure 5 is a plan sectional view taken at the line 5-5 on Fig. 4 and viewed in the direction of the arrows, with certain parts shown unsectioned. Figure 6 is an end view of a plural-passage-equipped sleeve device which is rotatably carried by the tone arm and on which the reproducer devices, forming parts of the machine, are mounted. Figure 7 is a plan view of the sleeve-equipped extremity of the tone arm. Figure 8 is a face view of a pin-equipped ring with which the sleeve of Fig. 6 is provided and which forms one of the elements of the means by which the reproducer devices are shifted into different positions on the tone arm. Figure 9 is a view taken at the line 9 on Fig. 1 and viewed in the direction of the arrow and showing the position of the parts therein illustrated, at the conclusion of the playing of a record. Figure 10 is a similar view showing the positions assumed by these parts upon the lifting of the reproducer device out of engagement with the record at the conclusion of the playing of the latter; and Figure 11, a similar view showing one of the positions occupied by the parts during the operation of swinging the tone arm crosswise of the record in the return of the tone arm to the position it occupies preparatory to the next operation of lowering the reproducer device to the record for playing the latter.

As a preface to the following description of the invention, it may be stated that the reproducer-equipped tone arm of the particular construction of machine shown and which is represented at 12 is adapted to be swung both vertically and horizontally to the end that the reproducer device thereon may be lowered into engagement with the groove of the record to be played and represented at 13 and the needle or stylus of the reproducer device be free to bear yieldingly against the record and follow the spiral groove thereof to the end of the record groove and then lift it clear of the record and in raised position return it to the initial position shown in Fig. 1.

The machine shown is of a type comprising pneumatically controlled mechanism dis-

closed in the said application for patent, for automatically effecting the above described movements of the tone arm.

The tone arm 12 is shown as formed primarily of two sections 14 and 15 (Figs. 1, 3, 5 and 6) connected together by a joint represented at 16 adapting the section 15 to be swung on the section 14 in a substantially vertical plane, the section 14 being swiveled at 17 on the horizontal support 18, to adapt the tone-arm sections, as a unit, to be swung in a substantially horizontal plane about the substantially vertical axis afforded by the swivel 17, the reproducer portion of the machine, and hereinafter fully described, being mounted on the outer end of the tone-arm section 15.

The pneumatic by means of which the tone-arm section 15 is swung upwardly at its connection 16 with the tone-arm section 14, is represented at 19, (Figs. 1 and 2) the movable side of this pneumatic being provided with an outwardly projecting pin 20 which overlies the arc-shaped rear portion 21 of an arm 22 projecting rearwardly from the tone-arm section 15, the parts being so arranged that when the pneumatic 19 is collapsed the arm 15 and the reproducer portion thereof will extend in the raised position shown in the drawings. At the conclusion of the playing of a record the pneumatic 19 is collapsed for the purpose stated by the engagement of an arm 23 on the tone-arm section 14, with pneumatic controlling-mechanism represented at 24, the pneumatic 19 thus collapsed becoming locked in position by mechanism represented generally at 25. Upon setting the machine into action with the parts in the normal position shown in Fig. 1 a pneumatic represented at 26 is automatically actuated to release the lock 25 permitting the pneumatic 19 to expand, allowing the tone-arm section 15 to swing downwardly on the section 14 to lower the reproducer device into engagement with the record to start the playing of the record beneath it.

Upon concluding the playing of a selection, in which operation the tone arm swings in clockwise direction in Fig. 1, the arm 23 engages the pneumatic-controlling mechanism 24 to effect collapsing of the pneumatic 27 the movable side of which is connected with a push rod 28 extending through an opening in an arm 29 on the tone-arm section 14 and provided with a tappet 30 which in the operation of the pneumatic 27 as stated swings the tone arm at the swivel 17 in counterclockwise direction in Fig. 1 to the position therein shown, it being understood that the arm 15 remains in raised position, so that the needle or stylus is out of engagement with the record, during the horizontal swinging of the tone arm to normal position, as stated.

Referring now to the needle or stylus equipped portion of the mechanism, my in-

vention contemplates the provision of the tone arm with a plurality of reproducer units each complete in itself, it being preferred that four of these units represented generally at 31 be provided and grouped about the outer end of the tone arm section 15 and rotatable thereon for movement successively into position to engage the record groove. Each reproducer unit 31, which may be of any suitable construction, as for example that commonly provided in talking machines comprises a head 32 containing the diaphragm 33 with which the needle holder 34, pivoted at 35 on the head, is connected, the needle 36 of the reproducer device being preferably of such material that it may be used in the playing of a relatively large number of records without impairment; the reproducer device also comprises a tubular extension 37 on its head at which it is adapted to communicate with the tone passage.

The mounting for the reproducer devices on the tone-arm section 15 is shown as formed of a sleeve-like member 38 rotatably supported on the outer end portion 39 of the tone-arm section 15 and yieldingly pressed at one end against a shoulder 40 on this section, under the action of a spring 41 (Fig. 5) secured to a bar 42 extending beyond the journaling portion 39 and adjustably clamped to a bar 43 secured to, and extending axially of, the tone-arm section 15, the tone passage 44 in this arm extending short of the journaling portion 39 and opening through a side thereof as represented at 45. The free end of the spring 41 bears against the outer edge portion of the sleeve member 38 and is adapted to releasably enter notches 46 therein provided of a number corresponding with the number of reproducer units 31 and so arranged that one of these notches will be entered by the spring 41 when the corresponding reproducer device is so positioned axially about the tone-arm section 15 that its needle or stylus will be in proper position for entering the record groove.

The sleeve member 38 contains a series of radially-extending, equidistantly-spaced, openings 47 (Fig. 5) which open into tubular bosses 48 on the sleeve, the openings 47 successively moving into registration with the tone passage 44 in the rotation of the sleeve member 38, and the parts being so arranged that when the sleeve 38 is moved into a position in which said registration takes place the one of the reproducer devices in communication with the tone passage 44 will be in proper position for functioning.

The reproducer devices are mounted at their tubular portions 37 upon the tubular bosses 48 to extend radially from the axis of the tone-arm section 15, as shown.

The preferred illustrated embodiment of my invention also comprises means operating automatically each time the tone-arm

is swung at the swivel 17 to the position shown in Fig. 1 at the conclusion of the playing of a record, to move the reproducer device by which the record was played, out of operative position and move the next succeeding one of the reproducer devices into a position for effecting the next playing operation, whether it be of the same record or another record substituted therefor either by an automatic operation as in the machine of the said application for patent or by a manual operation, these means comprising a ring 49 surrounding the sleeve portion 38 and secured to a flange 50 on the latter as by screws 51, this ring being provided with a plurality of equidistantly spaced pins 52 which extend lengthwise of the axis of the member 38. The pins 52 are provided for co-operation with a lever 53 (Fig. 1) pivotally connected at 54 with a stationary post 55 and extending crosswise of the axes of the pins 52. The lever 53 tends to swing downwardly against the uppermost one of the pins 52 preferably with the aid of a spring 56 connected at its lower end with the post 55 and at its upper end with the lever 53. The lever 53 contains, in its underside, adjacent its outer end, a notch 57 (Fig. 9) a portion of a side wall of which is cut away as shown at 58 to provide a cam surface 59, and between the notch 57 and the pivot 54 with a notch 60, these notches being spaced apart a distance substantially equal to the distance between the axes of the pins 52.

The parts just described are so arranged that when the tone-arm is swung horizontally to return it to the position shown in Fig. 1 after the playing of a record, the pin 52 associated with the reproducer device extending opposite to the one by which the record was played, the tone-arm section 15 being in raised position (Fig. 10), will engage the cam surface 59 and strike the end wall 61 of the notch 57 which forms an abutment. As the tone-arm continues to swing horizontally to the position shown in Fig. 1, the abutting of the pin 52 referred to against the shoulder portion 61, causes the plural-reproducer head, formed of the sleeve 38 and the reproducer devices, to rotate against the resistance of the spring 41 in clockwise direction in Figs. 9, 10 and 11 (one of the intermediate positions of these parts in this operation being shown in Fig. 11), the next succeeding pin 52 being carried up and entering the notch 60 in which position of the parts the reproducer device next in succession to the one which was used in the previous playing operation, is caused to extend into a position in which, when the tone-arm section 15 is swung downwardly, this reproducer device will engage at its needle or stylus with the record to perform the next playing operation, the spring 41, in the shifting of the reproducer devices as stated, entering the next notch to

hold the sleeve 38 against accidental displacement about the tone-arm section 15.

The mechanism just described not only serves to perform the function just stated but also operates to lock the tone arm against swinging horizontally out of the position shown in Fig. 1, until, and unless, the tone arm section 15 is permitted to swing downwardly from the position shown in Fig. 3 which operation, in the particular illustrated construction of the machine, is performed by the releasing of the lock mechanism 24 to start the playing of a selection, as hereinbefore described.

The machine also comprises means (Figs. 1 and 3) operating to prevent accidental swinging of the tone arm horizontally to a position in which the needle or stylus engages the record groove beyond the beginning of the playing portion of the groove, should any force be exerted tending to swing the tone arm in clockwise direction in Fig. 1 after the pin 52 leaves the notch 60 and before the needle engages the record, these means comprising a guide member 62 rising from, and supported on, the support 18, this guide member being shown as formed of a post 63 carrying an angle plate 64 the upper edge portion of the flange 65 of which is outwardly deflected as represented at 66, the flange portion 65 being so positioned that it is engaged by the outer end of the pin 43 as the tone arm section 15 swings downwardly, but so disposed that this pin extends entirely beneath it immediately preceding the lowering of this pin to its final position in the engaging of the needle or stylus of the reproducer device with the record groove.

While I have illustrated and described a particular embodiment of my invention, I do not wish to be understood as intending to limit it thereto as the same may be variously modified and altered without departing from the spirit of my invention. Furthermore, while I have illustrated the invention as embodied in a machine of a particular type, I do not wish to be understood as intending to limit it to embodiment in such a type of machine, as it may be incorporated in various other types and constructions of machine within the spirit of the invention.

What I claim as new and desire to secure by Letters Patent, is:

1. In a talking machine, the combination of a record-support, a tone-passage-equipped supporting member mounted for movement relative to said support, and a plurality of reproducer-devices mounted on said member and bodily movable into and out of operative position relative to the record and comprising substantially similar stylus holders.

2. In a talking machine, the combination of a record support, a tone-passage-equipped member movable relative to said support, and a plurality of reproducer-devices mounted on

said member for bodily movement thereon into and out of operative position relative to the record and comprising substantially similar stylus holders.

3. In a talking machine, the combination of a record support, a tone-passage-equipped member movable relative to said support and a plurality of reproducer devices rotatably mounted on said member for bodily movement thereon into and out of operative position relative to the record and comprising substantially similar stylus holders.

4. In a talking machine, the combination of a record support, a member containing a tone passage and movable relative to said support, and a plurality of reproducer devices each containing a tone passage and movably mounted on said member for communication at its tone passage with the passage in said member and for operative positioning thereon relative to the record and comprising substantially similar stylus holders.

5. In a talking machine, the combination of a record-support a member containing a tone passage and movable relative to said support, and a plurality of reproducer devices each containing a tone passage and rotatably mounted on said member for communication at its tone passage with the passage in said member for operative positioning thereon relative to the record and comprising substantially similar stylus holders.

6. In a talking machine, the combination of a record-support, a tone arm mounted to swing about a vertical axis and having a portion mounted to swing vertically, a plurality of reproducer devices mounted on said arm for bodily movement thereon into operative position relative to a record on said support, and means for actuating said arm at the conclusion of the playing of a record for lifting the reproducer device clear of the record and returning said arm to starting position.

7. In a talking machine, the combination of a record-support, a tone arm mounted to swing about a vertical axis and having a portion mounted to swing vertically, a plurality of reproducer devices rotatably mounted on said arm for bodily movement thereon into operative position relative to a record on said support, and means for actuating said arm at the conclusion of the playing of a record for lifting the reproducer device clear of the record and returning said arm to starting position.

8. In a talking machine, the combination of a record-support, a supporting member mounted for movement relative to said record-support, a plurality of reproducer-devices mounted on said member and bodily movable into and out of operative position relative to a record on said support, and means operating automatically after the concluding of the playing of a record, to bodily move the one of said reproducer devices by

which the record was played out of operative position and bodily move another of said devices into operative position.

9. In a talking machine, the combination of a record-support, a tone-passage-equipped member movable relative to said record-support, a plurality of reproducer-devices mounted on said member for bodily movement thereon into and out of operative position relative to a record on said support, and means operating automatically after the concluding of the playing of a record, to bodily move the one of said reproducer devices by which the record was played out of operative position and bodily moving another of said devices into operative position.

10. In a talking machine, the combination of a record-support, a tone-passage-equipped member movable relative to said record-support, a plurality of reproducer devices rotatably mounted on said member for bodily movement thereon into and out of operative position relative to a record on said support, and means operating automatically after the concluding of the playing of a record, to bodily move the one of said reproducer devices by which the record was played out of operative position and bodily move another of said devices into operative position.

11. In a talking machine, the combination of a record-support, a tone arm mounted to swing about a vertical axis and having a portion mounted to swing vertically, a plurality of reproducer devices mounted on said arm and bodily movable into and out of operative position relative to a record on said support, means for actuating said arm at the conclusion of the playing of a record for lifting the reproducer device clear of the record and returning said arm to starting position, and means operating automatically in the swinging of said arm, to bodily move the one of such reproducer devices by which the record was played out of operative position and bodily move another of said devices into operative position.

12. In a talking machine, the combination of a record-support, a tone arm mounted to swing about a vertical axis and having a portion mounted to swing vertically, a plurality of reproducer devices mounted on said arm and bodily movable into and out of operative position relative to a record on said support, means for actuating said arms at the conclusion of the playing of a record for lifting the reproducer device clear of the record and returning said arm to starting position, and means operating automatically in the swinging of said arm to starting position, to bodily move the one of such reproducer devices by which the record was played out of operative position and bodily move another of said devices into operative position.

13. In a talking machine, the combination of a record-support, a tone arm mounted to

- swing about a vertical axis and having a portion mounted to swing vertically, a plurality of reproducer devices mounted on said arm for bodily movement thereon into operative position relative to a record on said support, 5 means for actuating said arm at the conclusion of the playing of a record for lifting the reproducer device clear of the record and returning said arm to starting position, and 10 means operating automatically in the swinging of said arm, to bodily move the one of such reproducer devices by which the record was played out of operative position and bodily move another of said devices into operative position. 15
14. In a talking machine, the combination of a record-support, a tone arm mounted to swing about a vertical axis and having a portion mounted to swing vertically, a plurality 20 of reproducer devices mounted on said arm for bodily movement thereon into operative position relative to a record on said support, means for actuating said arm at the conclusion of the playing of a record for lifting the 25 reproducer device clear of the record and returning said arm to starting position, and means operating automatically in the swinging of said arm to starting position, to bodily move the one of such reproducer devices by 30 which the record was played out of operative position and bodily move another of said devices into operative position. 35
15. In a talking machine, the combination of a record-support, a tone arm mounted to swing about a vertical axis and having a portion mounted to swing vertically, a plurality 40 of reproducer devices rotatably mounted on said arm for bodily movement thereon into operative position relative to a record on said support, means for actuating said arm at the conclusion of the playing of a record for lifting the 45 reproducer device clear of the record and returning said arm to starting position, and means operating automatically in the movement of said arm to starting position, to bodily move the one of said reproducer devices by which the record was played out of operative position and bodily move another of said devices into operative position. 50
16. In a talking machine, the combination of a record-support, a tone-passage-equipped member movable relative to said support, a second member rotatably mounted on said first-named member, and a plurality of reproducer devices mounted on said second member for movement therewith on said first-named member. 55
17. In a talking machine, the combination of a record-support, a tone-passage-equipped member movable relative to said support, a second member rotatably mounted on said first-named member, a plurality of reproducer devices mounted on said second member for movement therewith on said first-named member, and means operating automatical- 60
- ly after the concluding of the playing of a record to rotate said second member for bodily moving the one of said reproducer devices by which the record was played out of operative position and bodily move another of said devices into operative position. 65
18. In a talking machine, the combination of a record-support, a tone-passage-equipped supporting member movable relative to said support, a plurality of reproducer devices mounted on said member and bodily movable into and out of operative position relative to a record, a series of projections operatively connected with said reproducer devices, and means with which said projections engage in movements of said member for bodily moving the reproducer devices. 70
19. In a talking machine, the combination of a record-support, a tone-passage-equipped supporting member movable relative to said support, a plurality of reproducer devices mounted on said member and bodily movable into and out of operative position relative to a record on said support, a series of projections operatively connected with said reproducer devices, and means with which said projections engage in the movements of said member to starting position for bodily moving the reproducer devices. 75
20. In a talking machine, the combination of a record-support, a tone-passage-equipped member movable relative to said support, a plurality of reproducer devices mounted on said member for bodily movement thereon into and out of operative position relative to a record on said support, a series of projections operatively connected with said reproducer devices, and means with which said projections engage in movements of said member for bodily moving the reproducer devices. 80
21. In a talking machine, the combination of a record-support, a tone-passage-equipped member movable relative to said support, a plurality of reproducer devices mounted on said member for bodily movement thereon into and out of operative position relative to a record on said support, a series of projections operatively connected with said reproducer devices, and means with which said projections engage in the movements of said member to starting position, for bodily moving the reproducer devices on said member. 85
22. In a talking machine, the combination of a record-support, a tone-passage-equipped supporting member movable relative to said support, a plurality of reproducer devices rotatably mounted on said member and bodily movable into and out of operative position relative to a record on said support, a series of projections operatively connected with said reproducer devices, and means with which said projections engage in movements of said member for bodily rotating the reproducer devices. 90
- 100
- 105
- 110
- 115
- 120
- 125
- 130

23. In a talking machine, the combination of a record-support, a tone-passage-equipped member movable relative to said support, a plurality of reproducer devices rotatably mounted on said member for bodily movement thereon into and out of operative position relative to a record on said support, a series of projections operatively connected with said reproducer devices, and means with which said projections engage in the movements of said member to starting positions, for bodily rotating the reproducer devices on said member.

24. In a talking machine, the combination of a record-support, a tone-passage-equipped supporting member movable relative to said support, a plurality of reproducer devices mounted on said member and bodily movable into and out of operative position relative to a record on said support, a series of projections operatively connected with said reproducer devices, and means with which said projections engage in movements of said member for bodily moving the reproducer devices comprising an abutment-device for engagement by said projections.

25. In a talking machine, the combination of a record-support, a tone-passage-equipped supporting member movable relative to said support, a plurality of reproducer devices mounted on said member and bodily movable into and out of operative position relative to a record on said support, a series of projections operatively connected with said reproducer devices, and means with which said projections engage in movements of said member for bodily moving the reproducer devices comprising a notched abutment-device for engagement by said pins.

26. In a talking machine, the combination of a record-support, a tone-passage-equipped supporting member movable relative to said support, a plurality of reproducer devices mounted on said member and bodily movable into and out of operative position relative to a record on said support, a series of projections operatively connected with said reproducer devices, and means with which said projections engage in movements of said member for bodily moving the reproducer devices comprising an abutment-device for abutment by said pins and containing a plurality of spaced apart pin-receiving notches.

27. In a talking machine, the combination of a tone arm provided with a reproducer device movable up and down and laterally, means holding said arm from movement laterally in the raised position of said device and disengageable therefrom in the lowering of said device, and a guide operative to guide said device to the record beneath it.

28. In a talking machine, the combination of a tone arm provided with a reproducer device movable up and down and laterally, means holding said arm from movement lat-

erally in the raised position of said device and disengageable therefrom in the lowering of said device, and a stationary guide operative to guide said device to the record beneath it.

29. In a talking machine, the combination of a record support, a tone-passage-equipped member movable relative to said support, a member rotatably mounted on said tone arm and open to said tone passage, and a plurality of similar reproducer devices each for use with the same kind of a stylus, mounted on, and grouped about, said member, for the purpose set forth.

30. In a talking machine, the combination of a record support, a tone-passage-equipped member movable relative to said support, a member rotatably mounted on said tone arm and open to said tone passage and having portions about its periphery for attachment thereto of similar reproducer devices, and a plurality of similar reproducer devices mounted on said member at said portions and each adapted for use with the same kind of stylus, said devices having means for supporting thereon substantially similar stylus holders.

31. In a talking machine, the combination of a record support, a tone-passage-equipped supporting member movable relative to said support, a plurality of reproducer devices mounted on said member and bodily movable into and out of operative position relative to a record on said support, a series of projections operatively connected with said reproducer devices, means with which said projections engage in movements of said member for bodily moving the reproducer devices comprising an abutment-device for abutment by said pins and containing a plurality of spaced apart pin-receiving notches, and a guide operative to guide the reproducer device to the record beneath it upon movement of the pin out of the notch.

32. In a talking machine, the combination of a tone arm provided with a reproducer device movable up and down and laterally, means holding said arm from movement laterally in the raised position of said device and disengageable therefrom in the lowering of said device, and a stationary guide having an upwardly extending portion forming a guide for said device to the record beneath it and having an outwardly inclined upper portion to ensure engagement of said device with said portion.

AXEL F. LARSON
